PORTABLE TELEVISION STAND

Walter P. Myers, 2958 W. Carroll Ave., Chicago, Ill.

Filed Jan. 2, 1964, Ser. No. 78,024

Term of patent 14 years

(Cl. D33—14)

I claim:

The ornamental design for a portable television stand, substantially as shown.
